RATION OF WEST VIRGINIA

TROLLEY FOR CURRENT DISTRIBUTING SYSTEMS

Application filed July 28, 1930. Serial No. 471,382.

REISSUED

This invention relates to current distributing systems and more particularly to systems useful in distributing current from one portion of a factory building to another and it is to be understood that this case is to be considered along with the co-pending application Serial Number 471,381, filed July 28, 1930 in the name of Harrison J. L. Frank et al.

10 This application relates to the trolleys which take current from the bus bars while the said application Serial No. 471,381 relates to the bus bars and ducts from which current is to be taken by the trolleys disclosed in this application.

15 It has been the practice heretofore in factory installations to install, at conveniently located points, outlets from which current may be taken from plug-in devices attached to the end of cords, etc. leading from electrically driven tools. Such installations are extremely disadvantageous in certain types of work, especially those where it is necessary for a factory worker, 25 having an electrically driven tool in his hand to go from one place to another while the tool is operating.

It has been found desirable to provide a 30 trolley system such that the worker can move his electrically driven tool along with the work all the while withdrawing current without interruption, and without creating danger due to snagging or short circuiting of the cords which conduct the current to the tool.

35 An object of this invention, therefore, is a means from which current can be taken "on the run".

40 A further object is a trolley including wheels adapted to ride on rails, wheels adapted to ride along bus bars withdrawing current therefrom, and tool supporting means, the current collecting wheels being connected by suitable electrical connectors to a cord which leads to the electrically driven tool supported by the trolley.

45 A further object is a current collector trolley which is adapted to ride along and be supported by a bus bar enclosing channel 50 or duct, the current collecting trolley being

provided with means to take current from the bus bars.

A further object is a novel form of trolley for use with multiphase currents, one which is so formed as to be incapable of mechanical and electrical connection to the bus bars in any but the proper direction, whereby flow of the current in an improper direction is prevented.

55 60 A further object is a novel form of trolley, one which is removable from the rails along which it rides only at the end of a rail section, thus forming a permanent, though movable, connection between current collectors and bus bars.

65 A further object is a trolley provided with sides which may be moved to or from each other and adapted to embrace between them a rail along which the trolley is movable, the construction thus permitting removal of the trolleys from a rail at any point desired, the trolleys being provided with means to open or close the sides whereby removal of the trolley from the rail is prevented except when it is the will of the operator 70 to remove it.

75 80 A still further object is a novel form of trolley of the character described in the preceding paragraph wherein a handle means projecting downwardly from the head portion of the trolley is provided with latch means to control movement of the sides of the trolley.

85 Another object is a novel form of roller contact, one which includes a copper tube or sleeve integrally fastened to the outer race of a conventional or standard roller or ball bearing.

90 A still further object is a novel form of trolley having separable head portions which are insertable in a bus bar enclosing duct and which when separated engage the duct and the bus bars, although movable along the latter. The trolley thus described 95 is so formed that when the head portions are caused to approach each other, current collection ceases and withdrawal of the trolley from the duct is permitted, the trolley being provided with means whereby the 100

operator can cause the head portions to approach or retract from each other.

A still further object is a trolley having separable head portions which are so shaped as to enter a duct when in one position and to be incapable of withdrawal therefrom when rotated to another position.

Still further objects are novel forms of current collecting devices for trolleys, including wheels, shoes, etc.

A still further object is a novel form of trolley, one which has a handle portion projecting from a head portion and offset therefrom, so as to prevent insertion of the trolley head in a duct in any but the proper direction, whereby flow of current in an improper direction is prevented.

A still further object is a novel form of trolley, one which includes a handle portion which projects downwardly from the duct enclosing the bus bars, and which is provided with a universal joint therein and means to lock the joint so as to rigidify the handle. It is also contemplated to provide the trolley with a means so connected to the separable head portions as to lock the universal joint only when the head portions are moved towards each other, that is to say, when removal of the trolley from the duct is desired.

Still other objects will readily occur to those skilled in the art upon reference to the following description and the accompanying drawings in which

Fig. 1 is a side view of one form of trolley as if taken in the direction of the arrow 1 of Fig. 2.

Fig. 2 is a view in elevation of the form of Fig. 1, parts being in section.

Fig. 3 is a side view of a second form of trolley as if taken on the arrow 3 of Fig. 4.

Fig. 18 is a section of Fig. 17 on line 18—18.

Balancer or semi-permanent type used with channels 75

Referring to Figs. 1 and 2, one form of trolley is shown as provided with a pair of side plates 20 and 21 joined to each other at the bottom by means of a bolt 22 disposed within a sleeve or bushing 23, the latter forming a tool or Pedwyn balancer support.

A base plate 25, U shaped in cross section joins and is secured to the plates 21 and 20 by means of bolts 26—27, the bolts 22—26—27 forming with the side plates a rigid, non-collapsible trolley construction. At the upper ends of the plates 20—21 there are disposed a plurality of roller or ball bearing

trolley wheels 29 and 30, there being four in all, they being secured to the side plates by means of the bolts 31 and 32. Also disposed on the side plates and projecting thru slots in the latter are a plurality of rollers

33 and 34, the securing means therefor being the straps 35 and 36 which are riveted to the side plates by means of the rivets 37 and 38. Secured to the base plate U shaped member

25 are a plurality of insulating blocks 40—41 upon one of which are disposed a plurality (in this case six) roller supports 42, 43 and 44, in each of which is disposed a collector wheel, 46, 47, and 48.

As shown in Fig. 1, insulating block 40 is cut away at 49 whereby roller support 44 and roller 48 are disposed slightly below the level of the corresponding parts 42—43—46—47 for reasons to be hereafter described. Secured to the blocks 40—41 etc. is

a plug and receptacle device not shown which is adapted to receive fuses and a cord leading to the tool, not shown, and adapted to be electrically connected thru plug and receptacle contacts to the collector wheels 46 and 48 in a manner which is also not shown.

A feature of this invention, disclosed in Figs. 1 and 2 is the form of collector wheels have been found useful in this type of trolley. Each of the supports 42—43—44 is provided with a member 51 which is pivoted to it at a point 52 and each of which supports rollers upon an axle 53, there being a spring 55 disposed on the block 40 and adapted to cause upward movement of part

51 thereby causing the roller supported thereby to be thrust upwardly in constant engagement with the bus bar.

In use, the trolley of Fig. 1 is disposed

upon a channel 60 which has downwardly extending flanges 61 and three phase bus bars 62-63-64 on its lower surface, the buses being insulated from one another and from the channel in an appropriate manner. The trolley is slipped on the channel or rail 60 at an end thereof, its wheels 29 and 30 riding on the upper surface, its wheels 33-34 engaging the side flanges 61 for absorbing side thrust and its collector wheels 46-47-48 engaging the under surface of the buses 62-63-64 respectively.

It will be observed that due to the displacement of bus 64 and collector wheel 48 it is impossible to insert the trolley in the channel in any position other than the one shown, this construction preventing contact 48 from engaging any but the bus 64, thus polarizing the trolley and preventing flow of current through the tool fed thereby in an improper direction.

Portable type used with channels

In Figs. 3 to 6 inclusive, there is shown a second form of trolley, one which is adapted for use with the channel type distributor disclosed in Figs. 1 and 5 but which is removable from the channel or rail at any point, the trolley being provided with separable sides whereby such removal is facilitated. In this form of trolley there is provided a handle 70 which extends upwardly into and is secured to a sleeve 71 which slides on the downwardly extending post 72 welded and secured to the base 73 of the trolley as indicated at 74. Secured to the base 73 are insulating blocks 75 upon which are secured the collectors 76-77 and 78, these last mentioned parts being similar to the corresponding parts of the form of Figs. 1 and 2. The base 73 is upwardly extended at 83 and 84 to form guides or thrust plates for the slotted side plates 86-87, upon which are supported the trolley wheels 88-89. The side plates are hingedly secured to the base plate by means of the hinges 91 and 92, secured to the base 73 by means of the bolts 93 and 94, the side plates 86-87 extending somewhat below the base plate 73 to provide portions which are joined and constantly attracted to each other by means of the constantly contracting coil spring 95. Upon the handle 70 there is provided an L-shaped latch member 96 secured to a wire 97 which in turn is secured to a latch 98 pivoted on the sleeve 71 at 99 and held down by a spring 100 secured to the sleeve 71 at the point 101.

When a trolley is to be placed upon a channel 103, its sides are separated or moved to the position shown in Fig. 5. The trolley is then placed under and against the channel and handle 70 is pushed upwardly against the bottom of the channel. Sleeve 71 moves upwardly on post 72 and links

104, connecting it with the side plates 86-87, are thrust outwardly, moving the side plates on their pivots 91-92 towards the channel, causing wheels 88 and 89 to be disposed above the channel 103. The parts are held in this position by means of the coil spring which acts exactly in line with the links 104 and by means of the latch hook 105 which prevents post 72 from moving upwardly in sleeve 71.

When a trolley is to be removed from a channel, its sides are to be separated and this is accomplished as follows: Latch member 96 is depressed, forcing hook 105 out of the sleeve 71 and the post 72, permitting relative separation of these parts. The handle 70 and sleeve 71 are pulled downwardly, wheels 88 and 89 resting on the channel 103, and the straight line linkage 104-104 is broken, thus permitting spring 95 to pull the lower portions of side plates 86-87 towards each other and causing their upper portions to separate, thus releasing the trolley from the channel.

It will be observed that the upper edges of side plates 86-87 are protected by fiber sleeves 108 which prevent the metal plates from bridging or engaging the buses in the event a trolley is inserted in a channel with its sides closed, or with one side inside the channel.

It will also be observed from Fig. 5, that the extensions 83-84 of the base 73, by virtue of their diverging lips 85, facilitate the proper mounting of a trolley on a channel, they abutting the lower edges of the channel sides and thus guiding the trolley into its proper position with respect to the channel.

Further, from Fig. 5, it will be seen that bolts 93-94 act as stops against which the hinges 93a-94a which connect the side plate extensions 86a-87a to the links 104 are adapted to abut, this construction preventing outward overtravel of the side plates 86-87 due to the tension of the spring 95.

Further, by virtue of its location, the coil spring constantly exerts a pull on the side plates, tending to hold them in desired position, open or closed.

Portable type—Used with duct

A third form of trolley, especially useful with lighter electrical loads, is disclosed best in Figs. 7 to 10 inclusive. In this form the trolley head is composed of two insulating blocks 130 and 131, block 130 being provided with pins 132 which slide through apertures in the block 131 whereby to guide blocks 130 and 131 with respect to each other. A bow spring 133 secured to block 131 constantly tends to move block 130 away from block 131 thus forcing the contacts 134 into engagement with the correspondingly located buses 135 in the duct 136, the contacts 134

- preferably being of the collector wheel type previously described. Disposed on the insulating blocks 130—131 are fuse clips 138 adapted to support fuses 139 in an obvious manner, there being three such fuses for each of the three phases represented by each of three buses 135; one of the buses 135 being grounded, for obvious reasons. Secured to the under side of block 131 is a handle 140 upon which is pivotally mounted the link or strap 141 which is connected to the block 130 and which passes through an aperture in the block 131. The lower end of link or strap 141 is secured to the pivoted crank 142 provided with a handle 143 whereby when the latter is pressed towards the handle 140, link 141 will pull downwardly, thus causing block 130 to approach block 131 to release the contacts 134 from the bus bars. 10 The trolley is provided with rollers 145 which prevent grabbing due to friction between the collector and the edges of the duct 136.

In Fig. 8 it will be seen that the collector head is elongated in cross section so that it can be inserted in the slot 147 of the duct 136 with its long axis parallel to the long axis of the duct, after which it is rotated 90 degrees so that its long axis will now be transverse of the duct, all of this taking place while handle 143 is held adjacent handle 140 and while head portions 130 and 131 are adjacent each other.

After the trolley has been rotated, handle 143 is released and blocks 130 and 131 move away from each other so that the contacts will engage the bus bars for current collection.

In this form, the trolley is supported on the buses themselves, unlike forms previously described wherein the trolley is supported on a structural steel rail or channel.

Further, contacts 134, which are described, are wheel type contacts, may be replaced by the shoe type contacts 234 disclosed in Figs. 9 and 10, they being secured to the insulating blocks 130 by means of rivets 148.

Further, in order to prevent the current conducting cords which lead from the trolley from becoming entangled and perhaps broken, causing shortcircuiting, etc., fibre tubes 149 are provided, these tubes enclosing the wires which are threaded therethru and thru the aperture 150 (Fig. 7) on the trolley handle.

Universal type—Used with ducts

A fourth type of trolley which is also used with ducts for light load, is disclosed in Figs. 11 to 14 inclusive. In this form, the separable blocks 130 and 131 of the forms of Figs. 7 and 8 are provided, and block 131 has secured thereto a pair of straps 160 between which is slidable the yoke 161 60 to which the head 130 is secured by means

of the bolt 162. Welded to the sleeve 160 is a support 164 in which is disposed a coil spring 165 which tends to press upwardly on yoke 161 and maintain head portions 130 and 131 separated. A pin 166 secured to the lower side of yoke 161 passes through support 164 and is disposed within the ring 168 of the universal joint, the ring being supported on and between straps 160 by trunnions 169 and bolts 170 and on and between the ears 172 of the tube 173 which forms an extension of the straps 160. On the lower end of the pin 166 is secured a chain or tension member 174, the latter being secured at its lower end to a sleeve or handle member 175 provided with a pivoted latch 176 having a hook 177 disposed within an aperture 178 of the sleeve 173 and held therein by means of the expanding spring 179.

When it is desired to place the trolley in a duct, the rigid trolley, whose parts are in the position shown in Fig. 11, is placed in the duct and rotated. Latch 176 is then pressed by the operator's hand, so that hook 177 is withdrawn from aperture 178, whereupon spring 165 causes separation of blocks 130, 131 and releases the universal ring 168.

When removal of the trolley is desired, handle 175 is pulled downwardly against spring 165 until the latch hook slides far enough down the sleeve 173 to engage within aperture 178.

Semi permanent type—Used with ducts

A fifth form of trolley, useful with the ducts disclosed in Fig. 7, is disclosed in Figs. 15 and 16. In this form the collector head 180 is provided with contacts 181 similar to those disclosed in Figs. 9 and 10 and with side thrust roller bearings 182 supported on axle forming straps 183 secured to the head by means of the bolts 184. In this form also the axis of the handle 186 is displaced with respect to the axis of the head 180 and of the duct 187, whereby improper rotation of the head in the duct is prevented, this form being insertable in the duct only from an end thereof.

Modifications

While there have been shown five different modifications of the trolley, it is obvious that other modifications can be made without departing from the spirit of the invention, whose scope is to be determined by the appended claims and not to be limited by the foregoing description.

For example, in the form of Fig. 1, the side plates may be joined to each other by means of a handle or extension rather than by means of a tool support. Further, the trolley wheels may be disposed at different points, in the event different shapes of rails are used. Also instead of having two col-

lector wheels for each phase as in Fig. 1, it is obvious that one or more than two may be used, if desired.

Similarly, in the form of Figs. 3 to 6, inclusive, the fuse clips may be disposed on the side rather than in the head and more than one collector wheel for each phase member used. Further, other means for releasing the trolley from the rail may be used, if desired.

In the forms of Figs. 7 to 10 inclusive, non-separating heads may be used, if desired, the device thus being made a more or less semi-permanent trolley. Further, the fuse clips may be provided on the handle rather than in the head 130—131. Furthermore, the guides 132 may be replaced by other guiding means or may be omitted altogether, if desired.

Similarly in Figs. 11 to 14, a different universal joint and different forms of locking means may be used, if desired.

In the form of Figs. 15 and 16 the handle 186 may be joined to the head 180 on the side thereof rather than at the bottom. Similarly, numerous other modifications may be designed and it is the intention of the applicant to consider all modifications as the full equivalent of those described and claimed.

Further, if desired, a roller contact of the form of Figs. 17 and 18 may be used. In this form a copper tube or sleeve 190 is fastened to the outer race 19 of a standard form of ball bearing, the latter being usually made of steel. The fastening may be performed in various ways, but it is preferred to swedge or sweat the tube onto the race. This form of roller provides a copper to copper contact between the roller and the copper bus bar and is therefore, superior to ordinary steel roller contacts not so equipped.

Now having described the invention and the preferred embodiment thereof, it is to be understood that the said invention is to be limited, not to the specific details herein set forth but only by the scope of the claims which follow:

1. A current collecting trolley including a pair of side plates, a contact support secured to and between said plates, contacts between the plates on said support, and trolley supports on and between said side plates, said contacts including collector wheels adapted to rotate against bus bars.

2. A current collecting trolley including a pair of side plates, a contact support secured to and between said plates, contacts between the plates on said support, and trolley supports on and between said side plates, said contacts including pivotally mounted collector wheels provided with springs adapted to urge said wheels against bus bars.

3. A current collecting trolley including a pair of side plates, a contact support se-

cured to and between said plates, contacts between the plates on said support, and trolley supports on and between said side plates, said side plates being joined to each other by a means which provides a tool support. 70

4. A current collecting trolley including a pair of side plates, a contact support secured to and between said plates, contacts between the plates on said support, and trolley supports on and between said side plates, 75 said side plates being readily movable away from each other whereby said trolley may be removed from the current distributor between them to which it is applied.

5. A current collecting trolley including 80 a pair of side plates, a contact support secured to and between said plates, contacts on said support, and trolley supports on said side plates, the collector being provided with fuse clips on said contact support 85 whereby fuses may be mounted on said support.

6. A current collecting trolley including a pair of side plates, a contact support secured to and between said plates, contacts on said support, and trolley supports on said side plates, 90 said side plates being separable from each other whereby said trolley may be removed from the current distributor to which it is applied, said contact support being 95 provided with means to guide and limit movement of said plates.

7. For use with a current distributor which includes a plurality of bus bars separated from each other, a current collector 100 including a pair of contact supports mounted so as to move towards and away from each other and adapted, when separated, to cause the contacts supported thereby to engage said bus bars, means tending to effect 105 separation of said supports, and means to cause said support to approach each other.

8. For use with a current distributor which includes a plurality of bus bars separated from each other, a current collector including a pair of contact supports mounted so as to move towards and away from each other and adapted, when separated, to cause the contacts supported thereby to engage said bus bars, and adapted, when adjacent 115 each other to permit removal of the collector from said distributor, means tending constantly to effect separation of said supports, and manually operated handle means to cause said supports to approach each other. 120

9. For use with an elongated current distributor having an elongated insertion slot in one surface, a current collector including a head portion whose length is approximately equal to the width of said distributor and whose width is approximately equal to the width of said slot, whereby said distributor may be inserted through said distributor only when its long dimension is parallel to the long dimension of said dis- 130

tributor and whereby said collector will remain in said distributor only when it has been rotated so that its long dimension is transverse to the long dimension of the distributor, the collector being provided with a handle to facilitate insertion and rotation of the head portion.

10. For use with an elongated current distributor having an elongated insertion slot in one surface, a current collector including a head portion whose length is approximately equal to the width of said distributor and whose width is approximately equal to the width of said slot, whereby said distributor may be inserted through said distributor only when its long dimension is parallel to the long dimension of said distributor and whereby said collector will remain in said distributor only when it has been rotated so that its long dimension is transverse to the long dimension of the distributor, the collector being provided with a handle to facilitate insertion and rotation of the head portion, said handle being offset from said head portion whereby the latter may be rotated in one direction only.

11. In a current collector, contact supports movable towards and away from each other, a bow spring between said supports constantly tending to separate them from each other, and a manually operable means to cause said supports to approach each other.

12. A current collector including contact supports movable to and from each other and a handle, said handle being provided with a universal joint and with means to move said contact supports towards each other.

13. A current collector including contact supports movable to and from each other and a handle, said handle being provided with a universal joint, with means to move said contact supports towards each other, and with means to lock said joint to rigidify said handle.

14. A current collector including contact supports movable to and from each other and a handle, said handle being provided with a universal joint, with means to move said contact supports towards each other, and with means to lock said joint to rigidify said handle, said locking means being so connected to said support moving means that actuation of the latter locks said joint.

15. A current collector including contact supports movable to and from each other and a handle, said handle being provided with a universal joint, with means to move said contact supports towards each other, and with means to lock said joint to rigidify said handle, said locking means being so connected to said support moving means that actuation of the latter locks said joint, the handle being provided with a latch which maintains the joint unlocked and

which permits the supports to remain separated.

16. A current collecting trolley including a pair of side plates, a contact support secured to and between said plates, contacts between the plates on said support, and trolley supports on and between said side plates, said contacts including spring urged collector wheels adapted to rotate against bus bars.

17. A current collecting trolley including a pair of side plates, a contact support secured to and between said plates, contacts between the plates on said support, and trolley supports on and between said side plates, said contacts including pivotally mounted collector wheels.

18. A current collecting trolley including a pair of side plates, a contact support secured to and between said plates, contacts between the plates on said support, and trolley supports including trolley wheels on and between said side plates, and mounted so as to rotate on a horizontal axis.

19. A current collecting trolley including a pair of side plates, a contact support secured to and between said plates, contact wheels between the plates on said support, and trolley wheels on and between said side plates, said side plates being joined to each other by a means which provides a tool support, said contact wheels being adapted to rotate against bus bars.

20. A current collecting trolley including a pair of side plates, a contact support secured to and between said plates, contacts between the plates on said support, and trolley supports on and between said side plates, said contacts including aligned pairs of collector wheels adapted to rotate against bus bars.

21. A current collecting trolley including a pair of side plates, a contact support secured to and between said plates, contacts on said support, and trolley supports on said side plates, certain of said contacts being displaced with respect to the remaining contacts, whereby improper application of said collector to a current distributor is prevented.

22. A current collecting trolley including a pair of side plates, a contact support secured to and between said plates, contacts on said support, and trolley supports on said side plates, said side plates being separable from each other whereby said trolley may be removed from the current distributor to which it is applied, there being spring means tending to separate said side plates from each other, the collector being provided with means to permit separation of said plate.

23. A current collecting trolley including a pair of side plates, a contact support secured to and between said plates, contacts on said support, and trolley supports on said

side plates, said side plates being separable from each other whereby said trolley may be removed from the current distributor to which it is applied there being spring means tending to separate said side plates from each other, the collector being provided with means to permit separation of said plate, said means including a latch device mounted upon a handle portion of said collector.

10 24. A current collecting trolley including a pair of side plates, a contact support secured to and between said plates, contacts on said support, and trolley supports on said side plates, said side plates being separable from each other whereby said trolley may be removed from the current distributor to which it is applied, there being spring means tending to separate said side plates from each other, the collector being provided with means to permit separation of said plate, said means including toggle joints adapted to be broken for plate separation.

25 25. For use with a current distributor which includes a plurality of bus bars separated from each other, a current collector including a pair of contact supports mounted so as to move towards and away from each other and adapted, when separated, to cause the contacts supported thereby to engage said bus bars, and adapted, when adjacent each other to permit removal of the collector from said distributor, means tending to effect separation of said supports, and means to cause said supports to approach each other.

30 35. A current collector including a pair of metallic side plates between which a current distributor is to be disposed, and insulators on the edges of said side plates adapted to prevent engagement of said side plates with said distributor.

40 45. A current collecting trolley including a pair of side plates, a contact support secured to and between said plates, contacts on said support, and trolley supports on said side plates, said side plates having insulator coverings on their upper edges.

HARRISON J. L. FRANK.
WILLIAM A. HARPER.
